UNITED STATES PATENT OFFICE

2,161,408

LIQUID CIRCULATING DEVICE

Curtis C. Coons, North Canton, Ohio, assignor
to The Hoover Company, North Canton, Ohio,
a corporation of Ohio

Application August 8, 1936, Serial No. 94,937

7 Claims. (Cl. 103—53)

This invention relates to fluid circulating devices and more particularly to devices adapted to lift a liquid a small distance and which are adapted to be hermetically sealed within a closed system such as a continuous absorption refrigerating system.

It is known to circulate fluids in a hermetically sealed system by means of an electromagnetically vibrated disc or fin. An example of a fin for circulating gas in a sealed system is disclosed in co-pending application of Daiger's Serial No. 21,920 filed May 17, 1935, now Patent No. 2,152,243. An electromagnetically operated diaphragm for circulating gas in a similar system is disclosed in co-pending application to Curtis C. Coons, Serial No. 24,675 filed June 3, 1935, now Patent No. 2,015,241.

It is an object of the present invention to provide means somewhat similar to the arrangement shown in the above mentioned co-pending applications which are adapted to circulate liquids or lift liquids a slight distance in a hermetically sealed system. Such pumps may be used to circulate absorption liquid between the boiler and the absorber of a continuous absorption refrigerating system or elsewhere in systems requiring that a liquid be lifted only a short distance or against a slight pressure.

It is another object of the invention to provide novel means for circulating a liquid.

It is still another object of the invention to provide a novel, electromagnetically operated pump for circulating liquid.

Other objects and advantages reside in certain novel features of the arrangement and construction of parts as will be apparent from the following description taken in connection with the accompanying drawing in which:

Figure 1 is a vertical cross-sectional view of a liquid circulator constructed in accordance with the present invention and illustrating one embodiment thereof.

Figure 2 is a vertical cross sectional view of a modified form of liquid circulator constructed in accordance with the principles of the present invention and

Figure 3 is a transverse cross sectional view of the circulator shown in Figure 2, the view being taken on the line 3—3 thereof.

Referring to the drawing in detail and first to the embodiment of the invention illustrated in Figure 1, it will be seen that the liquid pump is there illustrated as consisting of a closed casing which may be hermetically sealed and which

5 may also be employed.

Located in the bottom of the cup shaped casing 11 is an electromagnet 14. The core 15 of this magnet may be firmly secured to the bottom of the cup 11 by means of a weld as illustrated at 10 16. The bottom of the cup 11 or at least a portion thereof adjacent the electromagnetic pole 15 should be of non-magnetic material. A spool 17 is mounted upon the outside portion of the core 15 and is wound with insulated wire in accordance 15 with known practice, the insulated wire being shown at 18.

A disc or diaphragm 19 is mounted within the casing 11 with its central portion above the pole 15 of the electromagnet. For securing the diaphragm 19 in position, the screw 20 and spacing rings 21 may be employed. The diaphragm 19 may be provided with a number of holes as shown at 22 to aid in permitting liquid to pass from beneath the diaphragm to the upper surface thereof. 25

The liquid inlet to the casing 11 is shown at 23 and the arrangement should be such that the liquid level in the lower part of the casing should be slightly above the level of the diaphragm 19.

30 Mounted in the upper portion of the casing 11 is a catching pan or liquid receiving element 24 which is annular in shape and which has a central flange opening 25 located immediately above the pole piece 15 of the electromagnet and the center of the diaphragm 19. Secured to the top 35 of the casing 11 on the under side of the head piece 12 is a concave deflecting member 26 which is adapted to deflect liquid thrown upwardly by the diaphragm 19 and cause it to fall upon the catch basin 24. The outlet to the pump is shown at 40 and it will be seen that this is some distance above the inlet pipe 23, the difference in height being the distance that the pump lifts the liquid.

The operation of the device shown in Figure 1 results from the energizing of the coil 18 of the electromagnet 14 with alternating current or with pulsating direct current. In either case the electromagnet will cause the diaphragm 19 to vibrate. Vibrating liquid will be thrown upwardly against 45 the deflecting member 26 and fall down upon the catch basin 24 at the higher level. The diaphragm 19 in approaching the pole piece 15 of the electromagnet should be so positioned that the liquid will be forced upwardly through the 50 55

small holes 22 therein. The spray of liquid leaves the central part of the disc in a conically shaped column or spray which spreads out, umbrella like, as it rises. Passing through the flanged hole 25 in the catch basin 24, the liquid is either deflected by the member 26 or falls directly upon the catch basin 24 without hitting the deflecting member. While the deflecting member 26 improves the operation of the system its use is not absolutely essential. The under side of the deflecting member 26 may be grooved radially to aid in causing the liquid to be retained upon its surface, although this is not shown in the drawing.

15 Obviously by the use of a series of such disc pumps situated one above the other, a liquid could be elevated to any desired height.

The arrangement of Figure 2 is somewhat similar to that of the arrangement of Figure 1 except that a leaf spring or fin is used to throw the liquid instead of employing a disc.

20 As shown in Figure 2, a horizontally disposed cylindrical casing 27 houses the pumping apparatus and is provided with end pieces or heads 25 and 29. The inlet to the casing 27 is shown at 30 and the outlet at 31.

25 As in the arrangement of Figure 1 an electromagnet 14 is mounted in the bottom of the casing 27, the pole piece 15 being welded or otherwise hermetically sealed to the casing by means of the weld 16. A coil 18 is employed to energize the electromagnet.

30 In the arrangement of Figures 2 and 3 the vibrating fin is illustrated at 32 and is mounted upon the casing by means of the bolt 33 and the spacing ring 34, the free end of the fin being located above the pole piece 15 of the electromagnet. It may be provided with a number of holes as shown at 35, if desired. A catch basin 36 is mounted in the upper part of the casing 27 and is provided with a flanged opening 37 above the free end of the vibrating fin.

35 As the fin is vibrated up and down by means of the electromagnet 14, liquid is thrown from the free end thereof through the opening 37 and falls upon the catch basin 36 so that it may flow away through the discharge 31 of the pump. Due to the natural curvature of the cylinder 27 no deflecting member like that shown at 26 is necessary.

40 While only a few embodiments of the invention have been shown and described herein, it is obvious that various changes may be made in the arrangement and construction of parts without departing from the spirit of the invention or the scope of the annexed claims:

45 I claim:

1. A liquid pump adapted for lifting liquid a small distance in a hermetically closed system, said pump having an electromagnet, a movable element adapted to be vibrated by said electromagnet, means for causing liquid to be pumped to contact said movable element and be thrown thereby to a higher level and liquid catching

means located above said movable element and adapted to catch the liquid thrown thereby.

2. A liquid pump adapted for lifting liquid a small distance in a hermetically closed system, 5 said pump having an electromagnet, a movable element adapted to be vibrated by said electromagnet, means for causing liquid to be pumped to contact said movable element and be thrown thereby to a higher level and liquid catching means located above said movable element and adapted to catch the liquid thrown thereby, said movable element having holes therein through which the liquid may pass.

10 3. A liquid pump adapted for lifting liquid a small distance in a hermetically closed system, 15 said pump having an electromagnet, a movable element, adapted to be vibrated by said electromagnet, means for causing liquid to be pumped to contact said movable element and be thrown thereby to a higher level and liquid catching means located above said movable element and adapted to catch the liquid thrown thereby, said movable element comprising a disc disposed in a horizontal position with its center substantially above the core of said electromagnet.

20 4. A liquid pump adapted for lifting liquid a small distance in a hermetically closed system, 25 said pump having an electromagnet, a movable element adapted to be vibrated by said electromagnet, means for causing liquid to be pumped to contact said movable element and be thrown thereby to a higher level and liquid catching means located above said movable element and adapted to catch the liquid thrown thereby, said movable element comprising a flexible blade or 30 fin fixed at one end and having a movable end disposed near said electromagnet.

25 5. A liquid pump, comprising a receptacle for liquid, an electromagnet, a movable member 40 adapted to be vibrated by said electromagnet to throw liquid from said receptacle, said movable member having an aperture therein through which the liquid may pass, and means for catching the liquid thrown by said vibrating movable member.

30 6. A liquid pump, comprising a casing having bottom and side walls and adapted to contain a liquid, an electromagnet supported by the bottom wall of said casing, a movable member in and supported by said casing and adapted to be vibrated by said electromagnet to throw said liquid to a higher level, and means supported by the side walls of said casing above said movable member for catching the liquid thrown thereby to a 45 higher level.

35 7. A liquid pump comprising, a receptacle for liquid, an electromagnet, a movable member adapted to be vibrated by said electromagnet, being normally positioned above the liquid level in said receptacle and adapted to raise liquid from said receptacle, said member being so constructed as to allow liquid to pass from one side thereof to the other and means for catching liquid raised by said member.

CURTIS C. COONS.
